GOLF CART

Anthony T. Zagwyn, Delavan, Wis., assignor to AJ Industries Corporation, Delavan, Wis., a corporation of Wisconsin

Filed Dec. 2, 1968, Ser. No. 14,749

Term of patent 14 years

Int. Cl. D12—02

U.S. Cl. D14—3

I claim:

The ornamental design for a golf cart, as shown.
